UNITED STATES PATENT OFFICE.

WILLIAM DAVIS COVINGTON, OF VERNON, TEXAS.

PNEUMATIC KNEE PAD.

Application filed April 5, 1921. Serial No. 458,812.

To all whom it may concern:

Be it known that I, WILLIAM DAVIS COVINGTON, a citizen of the United States, residing at Vernon, in the county of Wilbarger and State of Texas, have invented certain new and useful Improvements in Pneumatic Knee Pads, of which the following is a specification.

This invention relates to pneumatic knee pads and more particularly to that class of devices adapted to be attached to the knees of a workman to prevent the abrasion of the knee and protection for the clothing.

One of the objects of the present invention is to improve the construction of knee pads and to provide a simple, yet durable and efficient pad designed for cotton pickers, carpenters and other mechanics and which will present a soft surface for the knee and prevent injury thereof while working in a field, or on a hard, cement floor and which may be comfortably worn by the workman at all times when in a kneeling position.

A still further object of the invention is the construction of a novel and improved knee pad for attachment to the leg of a workman such as a cotton picker, or other mechanic wherein a pneumatic cushion is afforded to protect the knee cap from injury and strain incident to remaining in a kneeling position for a long duration of time, and which pad will permit a person to walk easily without removing the same.

Another and very important object of the invention is the construction of a pneumatic knee pad of the type above set forth wherein a removable pneumatic cushioning element is provided for inflation to any desired degree to maintain the weight of the body, and protect the knees from injury including provision for inflating the bladder while retained by the knee pad.

An incidental object of the invention is the construction of a knee pad which will be extremely simple in design, consisting of comparatively few parts, inexpensive to manufacture, highly efficient in use for its intended purposes, strong, durable, and capable of universal use for the needs of agricultural as well as mechanical workers.

With these objects in view and others which will be manifest and suggested as the

purpose and nature of my invention are revealed in the following specification and drawings wherein I have shown a preferred embodiment thereof,

Figure 1 is a perspective view showing the knee pad when worn.

Fig. 2 is an open, plan view of the same.

Fig. 3 is a longitudinal sectional view of the pad as shown in Fig. 1.

Fig. 4 is an end view.

Fig. 5 is a detail sectional view showing the inner bladder and the inflating tube.

Referring to the drawings, a knee pad, in accordance with this invention, comprises a supporting member or element and a protecting member or element, each formed of flexible material, preferably leather. The protecting element is vertically disposed and extends at right-angles with respect to the forward end of the supporting member, as well as being hinged to the bottom of the supporting member.

The supporting member or element consists of a body portion which is semi-oval in cross section and comprises a curved bottom 12' and a pair of sides 12. The body portion is open at each end and at its top, and secured to the inner face of each of the sides 12, of the body portion, in any suitable manner, preferably by stitching, is a flat lengthwise extending rectangular flexible strip 13, of a length to extend from the rear end of and project beyond the forward end 75 of the body portion. Interposed between the rear end of the strip 13, and the rear ends of the sides 12, of the body portion, as well as being secured to said strip and said sides, preferably by stitching, is a vertically disposed end closure 14, formed of any suitable flexible material preferably leather. The closure 14, in connection with the strip 13, and body portion provides a semi-cylindrical pocket, closed at its rear end and opened 80 at its forward end, and in which is mounted a pneumatic cushioning element 15, provided with a valved air inlet nipple 16^a, which projects outwardly through one of the sides 12, of the body portion. The nipple 16^a is employed for inflating the element 15, when desired.

The protecting member is hinged, at its lower end, with the forward terminus of the

body portion of the supporting member and is constructed of flexible material, preferably leather, in fact the protecting member is formed from the extension of the material from which the supporting member is constructed, and the said protecting member consists of a vertically disposed body portion 11, which is semi-oval in plan and gradually decreases in width downwardly, 10 or in other words, the body portion 11, is tapered in side elevation. The body portion 11, is of greater height than the supporting member, as well as overlapping the forward ends of the sides 12, of the body portion of 15 the supporting member. The sides 11', of the body portion 11, of the protecting member the lower termini thereof disconnected from the supporting member, whereby when the protecting member is in its normal vertical position, the sides thereof will project 20 rearwardly with respect to the supporting member.

The flexible strip 13, as before stated, projects beyond the forward end of the body 25 portion and the projecting portion of the strip 13, extends into the protecting member and abuts against the inner face of the front wall of the latter.

The semi-cylindrical pocket formed by the 30 closure 14, strip 13 and body portion of the supporting member, provides for the convenient removal and insertion of the cushioning element 15, when occasion requires, or if the cushioning element 15, should be 35 come damaged it can be removed and a new one substituted.

To provide for securing the supporting and protecting members to the leg of the wearer, the rear end of the body portion has 40 connected thereto one end of a strap 16, and said rear end of the body portion of the supporting member is also provided with a buckle 17, to which the strap 16, is adapted to be connected. The top of the protecting 45 member, at the rear thereof, has secured thereto a strap 18, and has furthermore secured therewith a buckle 19, to which the strap 18 is adapted to be connected with. The strap 16, is vertically disposed, but the 50 strap 18, extends rearwardly and at an inclination and the manner of positioning the strap with respect to the wearer of the pad is shown in Figure 1.

For the purpose of maintaining the protecting member vertically disposed with respect to the forward end of the supporting member, a pair of rearwardly extending straps 20, are secured to the sides 11' of the protecting member, and which are adapted 60 to connect with buckles 21, secured to the

sides 12, of the body portion of the supporting member.

When the side straps 20, are released from the buckle 21, the leg may be straightened without loosening or disconnecting the pad from the wearer, under such conditions permitting the pad to be worn at all times when in the field or engaged in other work.

The protecting member prevents the entry of dust, dirt or gravel within the pocket or 70 beneath the knee, when the pad is secured to the leg of the wearer and furthermore, the forwardly projecting end of the strip 13, also assists in the preventing of the dust, dirt or gravel entering the pocket or into 75 the supporting member below the knee.

In the accompanying drawings, I have illustrated my invention embodied in one form by way of example, and which in practice has been found to be highly satisfactory 80 in obtaining the desired results. It will be obvious however that other embodiments may be adopted and that various changes in the details of construction may be resorted to by those skilled in the art 85 without departing from the spirit and scope of the invention. It is furthermore understood that the invention is not necessarily limited or restricted to the precise elements shown except in so far as such limitations 90 are specified in the subject matter being claimed.

Having shown and described my invention what I now claim as new and desire to secure by Letters Patent of the United 95 States is:—

A knee pad comprising a horizontally disposed semi-oval shaped supporting element, a vertically disposed tapering protecting member hinged at the lower terminus of its front to the forward terminus of the bottom of said element, said member overlapping throughout and extending above the forward terminal portion of said element and further projecting forwardly from said terminal portion, a vertical closure and a longitudinally extending flat strip secured together and arranged within and secured to said element and providing in connection therewith a semi-cylindrical pocket open at 110 the forward end of said element and with said hinged member constituting the sole closure for the open end of said pocket, a cushioning element mounted in and conforming in contour to the shape of the 115 pocket, and an attaching means for said element and member.

In testimony whereof, I affix my signature hereto.

WILLIAM DAVIS COVINGTON.
